CLAIM

The ornamental design for a battery-powered heating pad, as shown and described.

DESCRIPTION

FIG. 1 is a front perspective view of a battery-powered heating pad showing our new design;

FIG. 2 is a front elevation view of the battery-powered heating pad;

FIG. 3 is rear elevation view of the battery-powered heating pad;

FIG. 4 is a right-side elevation view of the battery-powered heating pad;

FIG. 5 is a left-side elevation view of the battery-powered heating pad;

FIG. 6 is a top plan view of the battery-powered heating pad; and,

FIG. 7 is a bottom plan view of the battery-powered heating pad.

The broken lines in the Figures show portions of the battery-powered heating pad that form no part of the claimed design.
